(57) **CLAIM**

The ornamental design for a waistcoat as shown and described.

DESCRIPTION

1. Waistcoat

1.1 : Front

1.2 : Back

1.3 : Left

1.4 : Right

1.5 : Left

1.6 : Right

1.7 : Left

1.8 : Right

1.9 : Perspective

1.10 : Perspective

1.11 : Perspective

1.12 : Perspective

Waistcoat with back pockets; the broken line outline of the partial human figure in FIGS. 1.11-1.12 assists in illustrating how the waistcoat may appear when in a position of use, but forms no part of the claimed design. The thin irregular lines on the surfaces of the claimed design show shading that

(Continued)

defines the contours of the waistcoat and do not reflect a particular surface ornamentation or material.

1 Claim, 12 Drawing Sheets
